F. A. FELDKAMP

CARTRIDGE FUSE

Filed Feb. 20, 1924

INVENTOR,
Frederick A. Feldkamp,
BY
Frauenthal & Richards,
ATTORNEYS.

UNITED STATES PATENT OFFICE.

FREDERICK A. FELDKAMP, OF NEWARK, NEW JERSEY.

CARTRIDGE FUSE.

Application filed February 20, 1924. Serial No. 694,002.

To all whom it may concern:

Be it known that I, FREDERICK A. FELDKAMP, a citizen of the United States, residing at Newark, in the county of Essex and State of New Jersey, have invented certain new and useful Improvements in Cartridge Fuses; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention relates, generally, to improvements in electric fuse devices; and the invention has reference, more particularly, to improvements in cartridge fuse devices provided with the blade type of terminal contact members.

The invention has for its principal object to provide a novel construction of cartridge fuse provided with means for rigidly holding the blade contacts against movement or displacement, so that the gap between the opposed internal ends of the blade contacts, which is bridged by the fusible element, is maintained at the desired predetermined dimension; thus avoiding accidental variations or changes of the gap dimension with the consequent change in the fuse rating, for increase in the length of the gap weakens the ampere rating of the fuse, and decrease in the length of the gap strengthens the ampere rating of the fuse. This invention also contemplates the use, in connection with the blade positioning and retaining means, of means for hermetically sealing the cartridge so that the internal pressure, induced by the blowing of the fuse element with the consequent vaporization of the metal of said fuse element, will tend to decrease the jumping distance of the arc and bring about a prompt quenching of the latter. In this connection it is desired to employ a suitable inert filler powder, and the invention also has for a further object to provide in connection with the blade contact holding means, an arrangement which 40 will permit of the easy and rapid filling and packing of the cartridge shell with the powder after the blades and said positioning and holding means therefor are in place.

Other objects of this invention, not at this 45 time more particularly enumerated, will be

clearly understood from the following detailed description of the same.

With the various objects of this invention in view, the same consists, primarily, in the novel construction of cartridge fuse provided with blade type terminals or contacts hereinafter set forth; and, the invention consists, furthermore, in the several novel arrangements and combinations of the various devices and parts, as well as in the details of the construction thereof, all of which will be hereinafter more fully described, and then finally embodied in the claims which are appended hereto.

The invention is clearly illustrated in the accompanying drawings, in which:

Figure 1 is a longitudinal vertical section through a cartridge fuse made according to and embodying the principles of this invention; Figure 2 is a transverse section taken on line 2-2 in Figure 1, and drawn on an enlarged scale; Figure 3 is another transverse section taken on line 3-3 in Figure 1, also drawn on an enlarged scale; and Figure 4 is a fragmentary longitudinal section, taken on line 4-4 in Figure 1, and also drawn on an enlarged scale.

Figure 5 is an inner face view of a modified form of blade contact positioning and holding means; Figure 6 is a side elevation of the same; and Figure 7 is a longitudinal section thereof, taken on line 7-7 in Figure 6.

Similar characters of reference are employed in all of the hereinabove described views, to indicate corresponding parts.

Referring now to said drawings, the reference character 1 indicates the tubular cartridge shell or casing which is made of any suitable electrically non-conductive material. The reference character 2 indicates the blade terminals or contact members of the device, the inner end portions 3 of which extend respectively into opposite ends of said shell or casing 1. Each blade terminal or contact is provided in its longitudinal edges with transversely opposite indented slots or notches 4, which are spaced forwardly or outwardly from the inner termination of the same, so as to determine the desired distance of projection of the inner end portions 3 of the blade terminal or contact into the interior of the shell or casing.

The means for positioning and holding each blade terminal or contact in desired

predetermined fixed disposition relative to the ends of the shell or casing 1, comprises, in the preferred form, a metallic washer member diametrically divided to provide 5 separable half-portions 5. The diameter of the washer member when its separable half-portions 5 are assembled operatively together is substantially equal to the external diameter of the shell or casing 1, so that when 10 assembled in the structure the marginal portions of the washer member will rest or abut upon the end of said shell or casing. The diametric marginal edge portion of each half-portion 5 of the washer member is cut 15 away, as at 6, to straddle the body of the blade terminal or contact 2. In thus cutting away said half-portions 5 of the washer member tongues 7 are left at each end thereof of which, when the half-portions 5 are assembled 20 together in operative relation to the blade terminal or contact, enter the indented slots or notches 4 so as to interlock with the blade terminal or contact to thus hold the latter against longitudinal play or displacement. Each half-portion 5 of said washer member is provided with a buttress lug 8 which is struck up out of the main body thereof bordering its diametric edge, and then turned at right angles to the plane 25 30 of the washer member. When the half-portions 5 of the washer member are assembled together in operative relation to a blade terminal or contact, said buttress lugs 8 respectively extend along and brace against 35 the respective faces of the inner end portion 3 of said blade terminal or contact, thus securely and rigidly holding the latter against lateral play or displacement. In thus striking out of the body of each half-portion 5 of the washer member the said 40 buttress lugs 8, the washer member is at the same time provided with openings 9, which may be employed as filling openings for the introduction into the interior of the shell 45 or casing 1 an inert filler powder 10 after the blade terminals or contacts and washer members are operatively positioned relative to the shell or casing, whereby the operation of so filling the shell or casing is greatly 50 facilitated.

A suitable fuse element 11 is fastened to and electrically interconnected between the inner end portions 3 of the opposite blade terminals or contacts 2.

55 In order to retain the blade terminals or contacts 2 with their positioning and holding washer members in proper assembled relation to the ends of the shell or casing 1, ferrules or caps 12 are provided which are 60 telescopically engaged over the ends of the shell or casing 1, and the end walls of which are slotted to permit the external end portions of the blade terminals or contacts to project outwardly therethrough. The said 65 ferrules or caps 12 are secured against dis-

placement from the ends of the shell or casing 1 by stakes 13 or by any other suitable means of fastening or attachment.

I find it highly desirable to hermetically seal the cartridge fuse in some instances, and 70 to accomplish such end I provide a sealing washer 14 of a suitable compressible and preferably fire-proof material, such, for example, as sheet asbestos. The sealing washers are disposed intermediate the end wall 75 of each ferrule or cap 12 and the outer face of the blade positioning and holding washer members. Said sealing washers 14 are slotted to permit the outward projection therethrough of the external ends of said blade 80 terminals or contacts. When the ferrules or caps 12 are applied to the shell or casing ends the same are pressed firmly down to squeeze or compress the sealing washers 14 so that the latter are very tightly pressed 85 around the blade terminals or contacts so that all crevices around the latter are tightly closed, and since the blade terminals or contacts are rigidly held against both lateral and longitudinal play or displacement the 90 joints or crevices do not tend to open up once they are thus closed by the sealing washers.

In practice the operations of assembling the various parts of the novel cartridge fuse 95 are carried on as follows:—

The fuse element 11 is connected between the inner end portions of the blade terminals or contacts, and one end of the shell or casing is first closed by a ferrule or cap 100 12 after the positioning and holding washer member and sealing washer are properly assembled with the blade terminal or contact arranged at said end. The positioning and holding washer for the opposite blade 105 terminal or contact is assembled therewith so as to abut against the opposite end of the shell or casing. The cartridge fuse is then upturned on its closed or capped end, and the filler powder 10 is thereupon introduced 110 through the filling openings of the then upper exposed positioning and holding washer member, while the cartridge fuse is subjected to vibratory motion which compacts the filling powder around the fuse 115 element and internal ends of the blade terminals or contacts. In this manner the filling powder will imbed all the internal parts including the buttress lugs 8, and all necessity of forcing parts into relative positions 120 after the shell or casing is filled with powder is avoided. After the shell or casing is filled with the powder, in the manner above described, the sealing washer and opposite ferrule or cap are assembled with the upper 125 end of the shell or casing, thus completing the cartridge fuse.

The cartridge fuse in its finished form is hermetically sealed, and consequently not only will the increased internal pressure pro- 130

duced at the moment of blowing of the fuse element, due to the gases produced by vaporization of the fuse element, tend to decrease the jumping distance of the arc, but will also cause a much more rapid extinction of the arc; furthermore, the hot gases will be confined within the shell or casing where they can do no harm, thus avoiding fire risks. The hermetically sealed cartridge can be employed without fear of over-pressure when a fuse element of high specific conductivity is employed, such, for example, like the fuse elements described in my prior Letters Patent No. 1,473,284, dated November 6th, 1923, and in my pending application for Letters Patent Serial No. 629,808, filed April 4th, 1923. These fuse elements consisting of copper are of the smallest mass for a given amperage, and therefore the pressure produced, when blowing under a short circuit, is safely within the limit of tensile strength of the shell or casing and within the limit of resistance to displacement offered by the ferrules or caps. The filler powder in conjunction with a fuse element of comparatively small mass also plays a part in reducing internal pressures within the range of safety.

It will be understood, however, that it may be desirable to employ the novel means for positioning and holding the blade terminals or contacts without regard to whether the cartridge fuse is of the hermetically sealed type or not, and consequently, as to this feature of my invention I intend to claim the same broadly for use with any kind of cartridge fuse as well as specifically in combination with a hermetically sealed cartridge fuse as above described.

Referring now to Figures 5 to 7 inclusive of the drawings, I have shown therein a somewhat modified form and construction of the novel positioning and holding washer member, which nevertheless embodies the general principles of this invention. This modified form of positioning and holding washer involves a one-piece construction, comprising a main body 15 of disc-like form, having a diameter substantially equivalent to the external diameter of the tubular shell or casing with which it is to be used. Said main body is provided with a diametrically disposed slot 16 corresponding in dimensions to the cross-sectional dimensions of the blade terminal or contact 17 with which it is to cooperate, so that the latter may be inserted therethrough. Said blade terminal or contact is provided with indented slots or notches 18 in its opposite longitudinal edge portions. Struck out of the body 15 of washer-member so as to respectively border opposite sides of said slot 16, and respectively adjacent to each end of the latter are upturned buttress lugs 19 which project in planes at right angles to the plane of said washer member. In thus striking up said

butress lugs 19, arcuate concentric internal marginal portions 20 are provided to extend respectively in opposite directions from opposite sides of an adjacent to opposite ends of the slot 16. In assembling the blade terminal or contact 17 with the washer member thus formed, the former is inserted through the slot 16 until its slots or notches 18 are respectively opposite the ends of said arcuate portions 20, the position being that shown by the dotted lines in Figure 5. The blade terminal or contact is then given a quarter turn in the direction of the dotted arrow in said Figure 5, thus causing the arcuate portions 20 to enter the indented slots or notches 18 to hold the blade terminal or contact against longitudinal displacement, while at the same time engaging the buttress lugs 19 respectively against opposite sides or faces of the blade terminal or contact to hold the same against lateral play or displacement. The striking up of said buttress lugs 19 out of the body of the washer member also provides the filling openings 21 through which a filler powder may be introduced into the shell or casing with which the blade terminal or contact and the washer member are used. After the modified form of washer members have been assembled with the blade terminals or contacts, the cartridge fuse parts are assembled together and completed in the same manner as already above described.

I claim:

1. In a cartridge fuse, a tubular shell, blade-terminals, end caps, and blade holding and positioning washer members engaged between the ends of said shell and said end caps, each washer member having portions interlocked with a blade terminal to hold the latter against longitudinal displacement, and each washer member having buttress lugs struck up from the body thereof to respectively engage and brace opposite sides of said blade terminal.

2. In a cartridge fuse, a tubular shell, blade-terminals, end caps, and blade holding and positioning washer members engaged between the ends of said shell and said end caps, each washer member having portions interlocked with a blade terminal to hold the latter against longitudinal displacement and each washer member having buttress lugs struck up from the body thereof to respectively engage and brace opposite sides of said blade terminal, the upturning of said buttress lugs out of the body of said washer member providing openings in the latter for the introduction therethrough into the interior of said shell of a suitable filler powder.

3. In a cartridge fuse, a tubular shell, blade-terminals, end caps, and blade holding and positioning washer members engaged between the ends of said shell and said end caps, each blade terminal having in its

longitudinal edge portions transversely opposite indented slots, each washer having portions engaged in said slots to hold said blade terminal against longitudinal displacement, and each washer member having buttress lugs struck up from the body thereof to respectively engage and brace opposite faces of said blade terminal.

4. In a cartridge fuse, a tubular shell, 10 blade terminals, end caps, and blade holding and positioning washer members engaged between the ends of said shell and said end caps, each blade terminal having in its longitudinal edge portion transversely 15 opposite indented slots, each washer having portions engaged in said slots to hold said blade terminal against longitudinal displacement, and each washer member having buttress lugs struck up from the body thereof 20 to respectively engage and brace opposite faces of said blade terminal, the upturning of said buttress lugs out of the body of said washer member providing openings in the latter for the introduction there- 25 through into the interior of said shell of a suitable filler powder.

5. In a cartridge fuse, a tubular shell, blade terminals, end caps, and blade holding and positioning washer members engaged between the ends of said shell and said end caps, each washer member being diametrically divided to provide separable halves to embrace opposite sides of said blade terminal, each half of said washer 35 member having portions interlocked with said blade terminal to hold the latter against longitudinal displacement, and each half of said washer member having struck up from its inner diametric marginal portion a but- 40 tress lug, said buttress lugs being respectively engaged in bracing relation to opposite side faces of said blade terminal.

6. In a cartridge fuse, a tubular shell, 45 blade terminals, end caps, and blade holding and positioning washer members engaged between the ends of said shell and said end caps, each washer member being diametrically divided to provide separable halves to embrace opposite sides of said 50 blade terminal, each half of said washer member having portions interlocked with said blade terminal to hold the latter against longitudinal displacement, and each half of said washer member having struck up from its inner diametric marginal portion a but- 55 tress lug, said buttress lugs being respectively engaged in bracing relation to opposite side faces of said blade terminal, the upturning of said buttress lugs providing 60 openings in each half of said washer member for the introduction therethrough into the interior of said shell of a suitable filler powder.

7. In a cartridge fuse, a tubular shell, 65 blade terminals, end caps, and blade holding

and positioning washer members engaged between the ends of said shell and said end caps, each blade terminal having in its longitudinal edge portions transversely opposite indented slots, each washer member 70 being diametrically divided to provide separable halves, each diametric edge portion of each half of said washer being cutaway to embrace a blade terminal and provided with tongues at each end of said diametric 75 edge portions to enter said indented slots of said blade terminal, and each half of said washer member having struck up from its inner marginal portion bordering a face of said blade terminal a buttress-lug turned 80 inwardly at right angles to the plane of the washer member and edgewise to the face of said blade terminal.

8. In a cartridge fuse, a tubular shell, 85 blade terminals, end caps, and blade holding and positioning washer members engaged between the ends of said shell and said end caps, each blade terminal having in its longitudinal edge portions transversely 90 opposite indented slots, each washer member being diametrically divided to provide separable halves, each diametric edge portion of each half of said washer being cutaway to embrace a blade terminal and provided with tongues at each end of said diametric 95 edge portions to enter said indented slots of said blade terminal, and each half of said washer member having struck up from its inner marginal portion bordering a face of said blade terminal a buttress-lug turned 100 inwardly at right angles to the plane of the washer member and edgewise to the face of said blade terminal, the upturning of said buttress lugs providing openings in each half of said washer member for the 105 introduction therethrough into the interior of said shell of a suitable filler powder.

9. In a cartridge fuse, a tubular shell, 110 blade terminals, end caps, and blade holding and positioning washer members engaged between the ends of said shell and said end caps, each blade terminal having in its longitudinal edge portions transversely opposite indented slots, each washer member being diametrically divided to provide separable halves, each diametric edge portion of each half of said washer being cutaway to embrace a blade terminal and provided with tongues at each end of said diametric edge 115 portions to enter said indented slots of said blade terminal, and each half of said washer member having struck up from its inner marginal portion bordering a face of said blade terminal a buttress-lug turned 120 inwardly at right angles to the plane of the washer member and edgewise to the face of said blade terminal, and a slotted sealing washer of comparatively compressible mate- 125 rial engaged over each blade terminal and compressed intermediate the end caps and 130

positioning and holding washer members to hermetically seal the interior of said shell.

10. In a cartridge fuse, a tubular shell, blade-terminals, end caps, and blade holding and positioning washer members engaged between the ends of said shell and said end caps, each washer member having portions interlocked with a blade terminal to hold the latter against longitudinal displacement, and each washer member having buttress lugs struck up from the body thereof to respectively engage and brace opposite sides of said blade terminal, and a slotted sealing washer of comparatively compressible material engaged over each blade terminal and compressed intermediate the end caps and positioning and holding washer members to hermetically seal the interior of said shell.

11. In a cartridge fuse, a tubular shell, blade-terminals, end caps, and blade holding and positioning washer members engaged between the ends of said shell and said end caps, each blade terminal having in its longitudinal edge portions transversely opposite indented slots, each washer having portions engaged in said slots to hold said blade terminal against longitudinal displacement, and each washer member having buttress lugs struck up from the body thereof to respectively engage and brace opposite faces of said blade terminal, and a slotted sealing washer of comparatively compressible material engaged over each blade terminal and compressed intermediate the end caps and positioning and holding washer members to hermetically seal the interior of said shell.

12. In a cartridge fuse, a tubular shell, blade terminals, end caps, and blade holding and positioning washer members engaged between the ends of said shell and said end caps, each washer member being diametrically divided to provide separable halves to embrace opposite sides of said blade terminals, each half of said washer member having portions interlocked with said blade terminal to hold the latter against longi-

tudinal displacement, and each half of said washer member having struck up from its inner diametric marginal portion a buttress lug, said buttress lugs being respectively engaged in bracing relation to opposite side faces of said blade terminals, and a slotted sealing washer of comparatively compressible material engaged over each blade terminal and compressed intermediate the end caps and positioning and holding washer members to hermetically seal the interior of said shell.

13. In a cartridge fuse, a tubular shell, blade terminals, end caps, and blade holding and positioning washer members engaged between the ends of said shell and said end caps, each blade terminal having in its longitudinal edge portions transversely opposite indented slots, each washer member being diametrically divided to provide separable halves, each diametric edge portion of each half of said washer being cutaway to embrace a blade terminal and provided with tongues at each end of said diametric edge portions to enter said indented slots of said blade terminal, and each half of said washer member having struck up from its inner marginal portion bordering a face of said blade terminal a buttress-lug turned inwardly at right angles to the plane of the washer member and edgewise to the face of said blade terminal, the upturning of said buttress lugs providing openings in each half of said washer member for the introduction therethrough into the interior of said shell of a suitable filler powder, and a slotted sealing washer of comparatively compressible material engaged over each blade terminal and compressed intermediate the end caps and positioning and holding washer members to hermetically seal the interior of said shell.

In testimony that I claim the invention set forth above I have hereunto set my hand this 14th day of February, 1924.

FREDERICK A. FELDKAMP.
